CARBONIC ELECTRODE BAR FOR GOUGING PURPOSES

Keigo Momose, Koji Ishihara, and Kojiro Matsuo, Osaka, Japan, assignors to Matsushita Electric Industrial Co., Ltd., Kadoma-shi, Osaka, Japan

Filed Aug. 4, 1970, Ser. No. 24,303

Claims priority, application Japan May 29, 1970

Term of patent 14 years

Int. Cl. D8—99

U.S. Cl. D26—1

FIG. 1

FIG. 2

FIG. 3

FIG. 4

FIG. 1 is a front elevation of a carbonic electrode bar for gouging purposes embodying our new design shown broken away to indicate indeterminate length;

FIG. 2 is a side view thereof, the rear view and other side view of the same, being identical thereto;

FIG. 3 is a top view thereof; and

FIG. 4 is a bottom view thereof.

We claim:

The ornamental design for carbonic electrode bar for gouging purposes, as shown and described.
